UNITED STATES PATENT OFFICE.

JOSEPH SHUBERT, OF BRADDOCK, PENNSYLVANIA.

WHEELED TOY.

Application filed October 3, 1921. Serial No. 505,204.

To all whom it may concern:

Be it known that I, JOSEPH SHUBERT, a citizen of Poland, having first papers for United States citizenship, and resident of 5 Braddock, in the county of Allegheny and State of Pennsylvania, have invented certain new and useful Improvements in Wheeled Toys, of which the following is a specification.

10 This invention relates to wheeled toys and more particularly to a manually propelled wheeled toy having the appearance of an aeroplane, and has for one of its objects the provision of a toy of this character 15 that will be provided with suitable driving mechanism adapted to be operated by the operator's feet and an improved and novel steering mechanism.

20 A still further object it to provide a toy of the character described having the novel combination, construction and design of parts described in the following specification and illustrated in the accompanying drawings.

25 In the drawings, Figure 1 is a top plan of a toy constructed in accordance with my invention.

Figure 1^a is a fragmentary top plan of 30 the forward end of the toy, partly broken away to show the propeller driving mechanism and other working parts.

Figure 2 is a side elevation of the toy.

Figure 3 is a front elevation of the toy.

Figure 4 is a rear elevation of the toy.

35 Figures 5 and 6 are fragmentary detail views of the braking mechanism.

Referring more particularly to the drawings the numeral 1 designates the body of the toy as a whole, which is in the form of 40 a narrow bar and has a pair of outwardly lowered forward legs 3-3 in which is journaled a tractor wheel axle 7 having supporting tractor wheels 8 secured thereto. A supporting and steering wheel 16 is mounted 45 on an axle 17 journaled in suitable bearings in the lower end of a post 13 pivotally mounted in the body 1 adjacent its rear end. A seat 10 is also secured on the body 1.

50 A pair of wing members 40 and 43, held in vertical spaced relation by uprights 42, are secured to the body 1 adjacent its forward end and project laterally therefrom.

55 A substantially rectangular casing 30 having a mesh front wall is secured to the forward end of the body and resembles a radiator such as used on some forms of aero-

planes. The casing 30 has a bearing member 31 mounted in its forward wall which serves to support a propeller shaft 35 having a propeller 36 secured thereon. A counter-shaft 32 is journaled in the casing 30 and carries a beveled gear 33 which meshes with a beveled gear 34 on the shaft 35. The shaft 32 is provided with a pulley 32^a which is connected by a belt 38 with a pulley 39 on the axle 7. It will thus be apparent that as the vehicle is propelled the propeller will be rotated to give the appearance of a regular aeroplane propeller action.

60 A cross bar 5 is arranged between the legs 3 intermediate their ends to stiffen them and also to form a support for the forward end of a bar 6 which parallels the body bar 1 and serves to support a crank shaft 18. The rear end of the bar 6 is supported on a 65 bracket 6^a secured to the under side of the body bar 1.

70 The crank shaft 18 carries pedals 18^a at each end adapted to be operated by the occupant of the seat 10 to propel the toy. A 75 sprocket 19 is secured on the crank shaft 18 and is connected to a sprocket 19^a on the axle 7 by a drive chain 20 to transmit the power from the crank shaft 18 to the axle 7.

80 A rearwardly inclined steering post or 85 column 24 extends through and is journaled in the body bar 1 and is provided with a hand wheel 21 at its upper end. A short transverse bar 25 is secured to and projects 90 outwardly from one side of the steering post adjacent its lower end. A second transverse bar 27 is mounted in a suitable aperture in the wheel post 13 and extends outwardly at each side thereof. A connecting rod 26 extends between the bars 25 and 27 and is 95 pivotally connected to each.

100 A rudder member 47 is pivotally mounted on a bracket member 45 extending from the rear end of the body bar 1. A cross bar 47^a is secured in spaced relation to the lower or bottom face of the rudder 47 and a connecting rod 46 extends between the bar 27 and bar 47^a and is pivotally connected to each of the bars. It will thus be apparent 105 that any movement of the steering post or column 24 will be transmitted to the wheel 16 and rudder 47 so as to cause a simultaneous movement of the wheel 16 and rudder 47.

110 A brake drum 29^a is mounted on the axle 7 adjacent one of the legs 3, and a brake band 29 is mounted around the drum 29^a and adapted to be operated by a pedal bar 28

which extends rearwardly into a position readily accessible by the operator's foot.

The operation of the toy will be readily understood. The operator will be seated in the seat 10 and will operate the pedals 18^a by his feet, thus propelling the tractor wheels 8 by means of the drive connection consisting of sprockets 19 and 19^a and chain 20.

10 As the tractor wheel axle 7 is rotated the propeller 36 will be caused to simultaneously rotate due to the drive connection consisting of pulleys 39, 32^a, belt 38, counter-shaft 32 and beveled gears 33 and 34.

15 The toy is readily steered by the operator turning the hand wheel 21 on the steering post or column 24 in the usual manner, which post is connected to the single rear steering wheel 16 and rudder 47 as heretofore described.

I claim:—

A riding toy in the form of an aeroplane comprising a body portion having a seat intermediate its ends, wings projecting laterally from said body adjacent its forward end, a rudder member pivotally mounted at the rear end of said body, a pair of combined supporting and tractor wheels mounted on an axle journaled in 25 downwardly extending legs adjacent the forward end of said body, a single combined

35 supporting and steering wheel mounted on a pivoted post adjacent the rear end of said body, means connecting said post and said rudder member to cause unison of movement thereof, a propeller wheel mounted on a horizontal shaft journaled in the forward end of said body, a crank shaft journaled in said body at a point below said seat and intermediate the seat and the tractor wheels, 40 pedals on said crank shaft to provide for the rotation of said shaft by the operator when in the seat, a sprocket on said crank shaft, a second sprocket on said tractor wheel axle, an endless drive chain trained over said sprockets, a countershaft journaled in said body and geared to said horizontal propeller shaft, a flexible driving connection between said tractor wheel axle and said countershaft, a steering post positioned 45 forward of said seat and adapted to be controlled by the operator, and a rigid connecting rod pivotally connected to said steering post and said pivoted steering wheel post, all substantially as shown and for the purposes described.

50 In testimony of this, I affix my signature in the presence of two witnesses.

JOSEPH SHUBERT.
